LIFE SAVING DEVICE FOR SUBMARINES

Herbert F. Good, Philadelphia, Pa., assignor of
three-twentieths to Frank Maddenford, Frank-
ford, Pa.

Application November 5, 1929. Serial No. 404,938

8 Claims. (Cl. 114—16.6)

This invention relates to submarine rescue devices, and more especially to novel means for releasing passengers and crew from a submarine in case the latter is disabled while submerged.

One of the objects of the invention is to furnish a releasably buoy which may be discharged from a submerged submarine while carrying one or more occupants, for the purpose of elevating the occupant or occupants to the water surface.

A further object is to provide such a buoy with means to facilitate the sending and receiving of wireless messages, whereby, upon the arrival of the buoy at the water surface, an occupant may call for aid.

Another object is to furnish means of this character in which the buoy is tethered to the submarine in such manner that after the occupant or occupants depart while the buoy is at the water surface, a person remaining within the submarine may wind the tethering cable to return the buoy to the submerged boat, so that passengers and crew may be rescued one after another.

Another object is to provide an apparatus of this character, in which the submarine is furnished with a tubular member to receive the buoy, the tubular member and buoy being provided with cooperating means to permit one within the submarine to rotate the buoy, in the tubular member to bring a door of the buoy into registration with an entrance door of the tubular member.

A still further object is to furnish the tubular member with ejecting means which may be actuated from within the boat so as to eject the buoy forcibly from the tubular member whenever necessary, for example, when some obstruction or the like has fallen across the buoy and tends to force the same into the tubular member, or to prevent the buoy from leaving the tubular member.

Another object is to provide an apparatus of this kind in which the unoccupied space remaining in the tubular member, while the buoy is within the latter, communicates at both ends and at both sides with air admission and discharge means, and water admission and discharge means, so that water may be introduced into the tubular member, and air may be discharged from the same while the submarine is either in upright position or lying upon either one of its sides.

With the foregoing objects outlined and with other objects in view which will appear as the description proceeds, the invention consists in the novel features hereinafter described in detail,

illustrated in the accompanying drawings, and more particularly pointed out in the appended claims.

In the drawings,

Fig. 1 is a transverse vertical sectional view of a submarine equipped with my improvements, 60 and showing the means employed for winding the buoy cable.

Fig. 2 is an elevation of a detail shown in Fig. 1, but illustrating the handle cable winding crank, while held out of engagement with the 65 main gear of the cable winding drum to permit the cable to rapidly unwind as the buoy rises.

Fig. 3 is a view similar to Fig. 1, but taken from the opposite side of the buoy housing or 70 tubular member.

Fig. 4 is a similar view but taken diametrically through the buoy tube or tubular member.

Fig. 5 is a sectional view of the buoy after it has risen to the water surface, and showing the tethering cable which keeps the same in touch 75 with the disabled submarine.

Fig. 6 is a top plan view of the buoy.

Fig. 7 is an enlarged elevation of the interior of the buoy cover, and showing the means employed for locking the same in its closed position. 80

Referring to the drawings, it will be noted that the present invention may be applied to any type of submarine 8. For example, between the deck 9 and floor 10 of the submarine, I may arrange 85 a tubular member 11, the upper end of which is open and the lower end of which is permanently closed, for example by the floor 10.

As shown in Fig. 4, this tube is normally occupied by a buoy 12 which has an annular flange 13 at its upper end to fit on the upper end of the tube 11 for normally closing the latter. The buoy has a doorway that is normally closed by a door 14 which is adapted to be brought into registration with the door 15 of the tube. When these doorways are in registration, and the doors are open, a person may pass from the interior of the submarine into the buoy, and the doors may then be closed to render the buoy air-tight, and to prevent any water which flows into the tube 11 from passing into the interior of the submarine. 90 95 100

At this point, let it be assumed that the parts are in the position shown in Fig. 1, and that the buoy is occupied and ready to ascend, while the submarine is lying disabled on the bottom of the sea or the like. At such time, those within the submarine may open a valve 16, which is in a pipe 17 that extends from the shell of the boat to the interior of the tube 11. Consequently, 110 when the valve is opened, the interior of the tube

will be flooded, so that the buoy will tend to rise. However, if it becomes stuck or is obstructed, it may be ejected by an ejector 18, the construction and operation of which will be hereinafter described.

The buoy has its lower end secured to a cable 19, and the other end of the cable is wound on a shaft or drum 20 which is journaled in the tubular member, and has its ends extending at diametrically opposite points through the wall of the tubular member; one of the extending ends being provided with a relatively large gear 21 which is fast on the shaft 20. While the buoy is rising and the cable unwinding, there will be no means obstructing the rotation of the gear 21. When, however, it is necessary to return the buoy to the tubular member, the gear 21 is placed in mesh with a smaller gear 22 that is fast on a shaft 23, supported by an arm or lever 24, which is mounted at one end upon a horizontal pivot 25 and provided at its other end with an operating handle 26. When the parts are in the position shown in Fig. 1, but with the buoy 12 out of the tubular member, a crank 27, fast on the shaft 23, may be rotated for the purpose of rotating the gear 21, so that the shaft 20 will be turned and wind the cable 19 upon said shaft. When the operating parts are in the position shown in Fig. 1, a hand operated bell-crank lever 28 bears upon the arm 24 to hold the gears in mesh, and as the gear 22 is provided with a ratchet and pawl (not shown), which prevents the same from rotating other than in a single direction, it will be understood that such means act to hold the buoy in the tube 11. When, however, the buoy is to be released, the operator first swings the bell-crank lever out of obstructing position, and then lifts the handle 26 so as to bring a finger 29 of the arm 24 into engagement with a notch 30 on the lever 28, as shown in Fig. 2, for the purpose of holding the operating gear 22 in inoperative position while the cable is unwinding.

It will be recognized that each time the buoy is drawn into the tube 11, its door may not be in alignment with the door of the tube 11, and for the purpose of obtaining such alignment, I provide the lower end of the buoy with a circular bevel gear 31, designed to engage a smaller bevel gear 32 arranged on one end of a shaft 33, whose other end has fixed thereto an operating handle or crank 34, as shown in Fig. 1. To insure the proper alignment of the doors, the tube 11 is provided with a window 35 through which an operator within the submarine may watch for a suitable indicator or mark placed on the exterior of the buoy.

As heretofore mentioned, the tube is provided interiorly with an ejector 18, and this ejector may have legs 36 to slide vertically in parallel guideways 37 arranged within the tube. The lower ends of the legs are provided with ears 38 which are connected to ends of cables 39 which pass over fixed pulleys 40 within the tube and have their opposite ends secured to a winding shaft 41, one end of which projects beyond the tube 11 and is provided with a large gear 42, actuated by a smaller gear 43 that is driven by a hand crank 44. Obviously, when the hand crank is turned in the proper direction, the cables 39 will be wound on the shaft 41, and the ears 38 will be pulled upwardly, and in turn they will push the ejector upwardly, so as to force the buoy out of the tube 11.

I prefer to make the cable 19 serve not only the purpose of a tethering rope for the buoy, but

also as line wires for signalling purposes. For instance, as shown in Fig. 3, the line wires 45 of the submarine may be connected to contacts 46 which bear upon a commutator wheel 47 that is mounted on the winding drum 20. In this way, the contacts may feed current to conducting wires forming part of the cable 19, and when the buoy is at the water surface, an occupant thereof may communicate with occupants of the submarine, or may erect an aerial, and send messages from the buoy or receive messages while occupying the buoy.

It will be obvious that after an occupant enters the buoy from the submarine, and while water is admitted to the tube 11 through the pipe 17, that the air in the tube must be displaced. For this purpose, I provide on the exterior of the tube 11, an air chamber 48 having a suitable gauge 49 and provided with a pipe 50 having a control valve 51. This pipe is connected by a vertical conduit 52 to horizontal conduits 53 and 54 which communicate by valved branches 55, 56, 57 and 58 with diametrically opposite sides and opposite ends of the tube 23. This more or less elaborate arrangement of piping has been provided to eliminate any failure of the structure to operate in case the submarine should be upon one of its sides or the other, with either the deck or keel uppermost. In other words, no matter what position of the submarine relatively to a horizontal plane, a valved outlet will always be present at a point high enough to allow the air to flow from the tube 11 into the tank 48 while the tube is being filled with water.

It will be recognized that the tube is not only filled with water when the buoy is to rise, but that when the buoy is returned to the tube, the tube will also be filled with water, due to the fact that its upper end was open while the buoy was out of the tube. Therefore, suitable means are provided to pump water from the tube 11 to allow a second occupant to get in the buoy after the first occupant has been rescued at the water surface. For this purpose, the apparatus includes a hand pump 59, the inlet branch 60 of which is connected by a pipe 61 to valved branches 62 and 63 that open into the lower portion of the tube at diametrically opposite points. The pipe 61 also communicates with the upper end of the tube by means of a pipe 64 which is joined to a horizontal conduit 65, whose opposite ends has valved branches 66 and 67 that communicate with the upper portion of the interior of the tube at diametrically opposite points. The outlet of the pump 59 has a valved branch 68 which leads through the shell of the boat to the exterior of the latter. This arrangement also allows pumping of water from the tube 11, regardless of the position of the latter. In other words, even though the boat is lying over on one side or the other, by manipulation of the proper valves, the pump may be actuated to force water from the tube and to discharge the same exteriorly of the boat.

To allow the buoy to descend relatively easy after an occupant has been rescued from the same at the surface of the water, I provide means to permit the buoy to be weighted down when desired. For this purpose, the buoy may be jackeded and provided with a water space 70 to which water may be admitted through a control valve 71 that preferably has a handle 72 which rises in the buoy, so as to be within easier reach of the operator. When an occupant is ready to leave the buoy, he will actuate the valve 71, so as to

flood the water space 70. Consequently, as the buoy becomes weighted, it will tend to sink and facilitate the redrawing of the same into the tube.

11. Of course, when the pump 59 is actuated, it will force water from the space 70, as well as from the interior of the tube.

I prefer to provide the buoy with a hinged cover 73 which may be locked and unlocked both from the exterior and the interior of the buoy. For this purpose, the hinged cover has a centrally disposed vertical rock shaft 74, the outer projecting end of which is fixed to a handle 75 that may be actuated from the exterior of the buoy. A disk 76 is fixed to the lower end of the shaft, and may be turned from within the buoy by means of a bail handle 77. This disk carries pivot pins 78, each one of which is pivotally connected to an ear 79 on a locking bolt 80. I prefer to employ four of these bolts, and to guide the same by pins 81 which depend from the cover. Each bolt has its upper edge inclined or slanted as shown at 82 in Fig. 5, and consequently, when the bolts are thrown, they will take under an annular surface 83 within the buoy, and not only lock the cover, but will draw the cover toward the buoy, so as to provide an effective seal.

So that the cover may remain opened if desired when the buoy is on the surface, it is preferred that the cover be provided with a pivoted hook 84 to engage the surface 83 and hold the cover in open position.

The buoy may also be provided with a window 85.

Assuming a submarine equipped with my apparatus, and the submarine becomes disabled, from the foregoing it will be understood that a rescue may be had, even though the submarine is lying substantially upside down on either one of its sides. When an accident happens, one of the crew for instance, will enter the buoy through the doors 15 and 14, and then these doors will be closed. Now, those within the submarine will raise the arm 24 from the position shown in Fig. 1, to the position shown in Fig. 2, so that the cable 19 may unwind while the buoy is rising. Then the valve 16 will be opened to flood the portion of the tube 11 that is not occupied by the buoy, and of course, the valve 71 should be closed by the occupant of the buoy to prevent the water from entering the jacket 70. Now, the buoy will tend to rise, due to buoyancy, but to insure this, those within the boat may turn the crank 44 to operate the ejector 18 for the purpose of starting the buoy to elevate.

55. As soon as the occupant of the buoy reaches the water surface, he can signal for help, and when he is ready for rescue, he will first open the valve 71 to flood the water space of the buoy, and then operate the handle 75 to close the buoy cover 73. 60. At such time, those within the boat will actuate the lever 28 to release the finger 29 and allow the gear 22 to mesh with the gear 21. Then the handle 27 will be rotated to wind the cable 19 and draw the buoy down into the tube 11. When the 65 buoy has been brought into the tube to the proper degree, the gear 31 will be in mesh with the gear 32. Consequently, those within the boat may turn the handle 34 to bring the doors of the tube and buoy into alignment. Now the proper one or ones 70 of the valves in the water lines will be opened, and the pump 59, when actuated, will force the water from the tube 11 and water jacket 70, and while this is going on, the air from the tank 48 is permitted to flow back into the tube 11 through 75 the proper valves in the air line.

The parts are now ready for a second one of the crew to be rescued, and after he has entered the buoy, the operation will be repeated.

To enable the water depth in the tube 11 to be seen, regardless of the position of the boat, I prefer to provide the tube 11 at opposite sides with gauge glasses 90 and 91.

From the foregoing description it is believed that the construction, operation and advantages of the invention may be readily understood by those skilled in the art, and I am aware that changes may be made in the details disclosed, without departing from the spirit of the invention, as expressed in the claims.

What I claim and desire to secure by Letters Patent is:

1. In combination, a submarine having a tube, a buoy adapted to enter the tube, means to permit an occupant of the submarine to enter the buoy, means for tethering the buoy to the submarine, and means for ejecting the buoy from the tube, said ejecting means being arranged in entirety at a lower elevation than the buoy and comprising legs projecting downwardly from the buoy, guide tracks for the legs, fixed pulleys, a winding shaft, and ropes passing over said pulleys and having certain of their ends connected to the lower ends of the legs, and their other ends connected to the winding shaft.

2. In combination, a submarine provided with a tube, a buoy normally occupying the tube and closing one end thereof, means to permit an occupant of the submarine to enter said buoy, means for pumping water out of the tube, and means including an air storage tank for introducing air into the tube as the water is pumped out.

3. In combination, a submarine provided with a tube, a buoy normally occupying said tube, means to permit an occupant of the submarine to enter the buoy, means for admitting water from the exterior of the submarine into said tube, a closed tank to receive air displaced by the water as the latter fills the tube, and means for forcing water out of the tube for emptying the latter.

4. In combination, a submarine provided with a tube, a buoy extending into said tube, means to permit an occupant of the submarine to enter said buoy, an air tank, and piping having valve controlled branches for placing diametrically opposite sides of the opposite ends of the tube in communication with said tank.

5. In combination, a submarine provided with a tube, a buoy normally extending into said tube and adapted to be used for transferring occupants of the submarine to the water surface, means to admit water into said tube, a pump, and piping connected to said pump and having valve controlled branches connected to diametrically opposite sides of the opposite ends of the tube to permit the pump to discharge water from various points of the tube.

6. The combination with a submarine and a buoy for transferring passengers from the submarine to the water surface, of a cover for the buoy, locking means for the cover, and actuating means for the locking means to permit the locking means to be operated from either the exterior or interior of the buoy, said locking means including a rotatable disk carried by the cover, and bolts pivotally connected to the disk and having inclined outer ends for engagement with surfaces of the buoy.

7. In combination, a submarine provided with a tube, a buoy normally occupying the tube and
